UNITED STATES PATENT OFFICE.

FRANK W. WATERMAN, OF BALTIMORE, MARYLAND, ASSIGNOR TO KEYES FIBRE COMPANY, OF WATERVILLE, MAINE, A CORPORATION OF MAINE.

MACHINE FOR MOLDING ARTICLES FROM PULP.

1,300,677.

Specification of Letters Patent.

Patented Apr. 15, 1919.

Application filed March 2, 1917. Serial No. 151,880.

To all whom it may concern:

Be it known that I, FRANK W. WATERMAN, a citizen of the United States, and resident of Baltimore, State of Maryland, have 5 invented an Improvement in Machines for Molding Articles from Pulp, of which the following description, in connection with the accompanying drawing, is a specification, like characters on the drawing representing 10 like parts.

This invention relates to improvements in machines for molding articles from pulp such as that disclosed in Patent No. 1,139,002 granted to me May 11, 1915, in which a series 15 of traveling molds having separable mold faces are supplied with a layer of pulp which is compressed between the mold faces to form a molded article.

In the apparatus disclosed in that patent, 20 as well as in all other pulp molding machines with which I am familiar, the mold members are subjected to heavy compression applied during a short interval in the travel of the mold so that the fluid content of the 25 pulp is squeezed out quickly.

By thus forcing the fluid out of the pulp rapidly minute streams are formed which carry away solid particles of the pulp and produce thin places or at times even holes in 30 the molded articles. Where the solid portions of the pulp are massed into lumps this rapid squeezing out of water fails to disintegrate the lumps thoroughly and leaves a hard spot or knot-like spot in the molded 35 article.

The principal object of the present invention is to provide a molding machine with means for applying a gradually progressively increasing pressure to the coöperating 40 mold members during a considerable, that is to say a relatively long, portion of the travel of the mold so that the liquid content of the pulp will be gradually squeezed out and the solid particles will have time to rearrange 45 themselves uniformly throughout the effective area of the mold faces.

By reason of this relatively slow expulsion of the fluid from the pulp the molded articles produced are of a superior quality 50 having a more uniform and homogeneous character throughout and the surface of the articles present a much smoother appearance.

Another object of the invention is to pro-

vide means for discharging flat molded articles, such as plates, from the molds without distortion. In machines for molding flat articles such as plates, it has heretofore been customary either to thrust the article from the mold by pressure upon its flat central 55 portion or to lift it from the mold by a suction device applied to the central portion of the article. As a consequence the central portion or base of the article is frequently bulged so that the molded articles do not 60 have the same holding capacity and do not 65 package readily.

My invention contemplates the removal of the article by pressure applied near its circumference, for example in removing plates 70 from the mold the pressure is applied to the under surface of the inclined peripheral wall of the plate. I have found that by discharging the plate in this manner its central portion is not distorted and that the pressure 75 applied to the marginal portion of the plate has no ill effect.

Other objects and features of the invention will more fully appear from the following description and the accompanying drawings and will be particularly pointed out in 80 the annexed claims.

In the drawings;

Figure 1 is a side elevation of a pulp molding machine embodying the preferred 85 form of my invention, the vat being shown in section,

Fig. 2 is an end elevation of the same, a portion of the wall of the pulp vat being broken away,

Fig. 3 is mainly a vertical sectional view on an enlarged scale through one of the molds, its supporting arm and hub, certain portions being shown in elevation, and,

Fig. 4 is a transverse sectional view 95 through the compression member of the mold illustrating in connection therewith the means for discharging the molded article from it.

The invention illustrated in the drawing 100 may be broadly described as comprising a series of traveling molds having separable members provided with mold faces with means for supplying a layer of pulp to said mold faces and means for exerting a gradually progressively increasing compression 105 upon said mold members during a considerable portion of the travel, one of the sepa-

rable mold members of each of the series being provided with means acting upon the under surface of the peripheral portion of the molded article to discharge it from the 5 mold.

The preferred embodiment of the invention is disclosed in the accompanying drawings as applied to a machine of the type disclosed in my prior Patent No. 1,139,002 10 10 aforesaid which comprises a pulp receptacle 1 into which the receiving members 2 of a series of traveling molds successively dip. The receiving mold members are carried upon the ends or formed integral with hollow 15 arms 3 which are radially attached to a central hub 4 which is keyed or otherwise rigidly secured upon a shaft 5 journaled in bearings in standards 6 which, as illustrated herein, are secured to the side walls 20 of the vat. It will, however, be understood that if the vat is sunken beneath the floor the supporting standards may be mounted upon the floor in proximity to the side walls of the vat. A pulley 7 fixed upon the shaft 25 25 serves to rotate it and the traveling mold members as will be readily understood.

Each of the mold supporting arms 3 is hollow to form a suction passage 8 which communicates with a port 9 in the hub 4 30 30 leading to one side thereof and which communicates during a portion of a revolution with a chamber from which the air has been partially or wholly exhausted. This construction is substantially like that disclosed 35 in my prior patent aforesaid.

In order to provide a machine of maximum capacity, and also to balance the machine so as to avoid lateral strains, the receiving mold is constructed in the form of 40 a chamber 10 having oppositely disposed open ends adapted to support two receiving mold faces, the chamber thereby serving as a common suction space for both of the receiving mold faces.

45 The mold faces may conveniently comprise perforated plates 11 covered with a wire screen 12 of fine mesh, the plates and their coverings being retained in place by a ring or cap 13 screwed upon the exterior 50 wall of the chamber 10.

In the operation of the machine the receiving mold sections are immersed in the pulp and suction applied to the hollow arm 3 so that layers of pulp will adhere to the 55 oppositely disposed mold faces. In view of the fact that the finer material is first deposited upon the mold faces by the suction and a smooth surface thereby formed, the perforated plates 11 and their overlying 60 mesh 12 are dished outwardly to present their convex sides to the pulp solution so that the inner face of the plates will be smooth.

The hollow supporting arm 3 preferably is offset and communicates substantially

tangentially with the suction chamber 10, the formation being such that the offset portion will serve to catch and remove the liquid contained in the chamber of the mold as the latter rises from the pulp vat. A 70 compressed air pipe 14 which communicates with the suction chamber at the side opposite the offset portion of the arm 3 provides a means for releasing the molded articles from the mold receiving faces in the manner disclosed in my prior patent aforesaid. 75

A pair of compression mold members 16 which are separable from the receiving mold members are mounted in coöperative relation with the oppositely disposed receiving 80 mold members, each of the compression members being mounted upon a supporting arm 17 which is pivoted upon a stud 18 projecting from a bracket or extension on the arm 3. A segmental gear 19 is operatively 85 connected to each arm 17 and coöperates with a reciprocatory rack 20. Each rack 20 is slidably mounted in a guide 21 supported upon the arm 3 and is provided with a roller or stud 22 which follows a cam 90 track 23 as the arm rotates.

In order to support the cam disks 24 in coöperative relation to the mold carrier the cam disks are provided with sleeves 25 which loosely surround the shaft 5 and are coupled 95 at their outer ends to anchoring devices which preferably comprise segmental bushing sections adapted to fit into the standards 6 and form the lower halves of bearings for the shaft 5. 100

In the operation of the machine, the rotation of the arm 3 which supports all of the coöperating mold members causes the rollers 22 to follow the cam track 23. The cam tracks are so formed that as each successive 105 mold member approaches the pulp in the vat, the racks 21 are moved inwardly, or toward the axis, causing the arms 17 which carry the compression mold members 16 to be raised away from the receiving mold 110 faces so that the receiving mold faces only enter the pulp within the vat.

When, upon further rotation the receiving mold faces with a layer of pulp adhering thereto are removed from the vat the cam 115 tracks 23 force the racks 20 outwardly thereby causing the segmental gear 19 to oscillate the arms 17 and force the compression faces lightly against the layer of pulp which adheres to the receiving mold face. 120

The compression mold members comprise faces which are substantial counterparts of the mold faces 12 of the receiving mold face 2. Heretofore these compression mold faces have been formed with a central movable 125 portion by which the molded article was discharged from the mold. In view of the distortion of the article resulting from this method of discharge the present compression mold face is so constructed as to have a pe- 130

ipherally movable member adapted to be actuated to detach and discharge the molded article from the mold.

- As illustrated in the accompanying drawings, particularly Fig. 4, the compression mold member comprises a centrally recessed body 28 secured rigidly upon the arm 17 or formed integral therewith. The body 28 is substantially of the size and contour of the receiving mold member and is provided with a covering plate 29 preferably having, a short distance from its margin, a peripheral groove 30 to provide a guideway for a peripheral portion 32 of the mold face. The outer wall of the groove is extended to form a flange 31 adapted in coöperation with the inner edge of the ring or cap 13 to shear off the material which extends beyond the periphery of the mold face. Both the central and peripheral portions of the mold face are perforated in the usual manner. The peripheral portion 32 of the mold face is provided with a series of pins or studs 35 which extend through suitable apertures in the plate 29 and engage a discharging plate or spider 36 which has a solid central portion 37 and is normally actuated by springs 38 to hold the peripheral mold member in molding position.
- As illustrated in Fig. 4 of the drawing, the springs 38 are shown as seated near the periphery of the central portion of the compression mold face and act normally to force the spider 36 backward so that the peripheral mold member will be withdrawn into the groove 31 and the mold properly assembled to coöperate with the receiving mold face to form a plate.
- The back of the compression mold member is provided with a transverse inclined guideway for an impinging member and has a central aperture 39 through which the impinging means may enter to engage the central portion 37 of the discharging plate or spider 36.
- A preferred form of impinging member which is illustrated herein comprises a spring actuated pin 40 which is telescopically mounted in an arm 41 depending from the sleeve 25 and projecting into the path of the body of the compression mold member. The pin 40 may conveniently be formed with a head 42 slidably fitting within a sleeve 43 which is adapted to be screwed into a socket 44 in the arm 41. A helical spring 45 of greater strength than the springs 38 bearing upon the base of the socket 44 and the head 42 of the pin normally holds the pin in extended position.
- In the operation of the machine the compression mold member passes beneath the depending arm 41 and the end of the stud 40 extending thereover engages the inclined surface 46 upon said member and rides up upon it. The pin is thereby forced back-
- ward against the compression of the spring 45 and retained in said position until the aperture 37 is reached, whereupon the pin is projected forward by the force of the spring and raps sharply upon the central portion 70 37 of the discharging disk 36. This forces the latter forward against the action of the springs 36 and projects the peripheral portion 32 of the compression mold face beyond its central portion, thereby detaching and 75 discharging the molded article. Upon further movement of the compression mold member the pin 40 rides up the oppositely inclined surface 47 thus releasing the discharging spider 36 so that it is returned by 80 the springs 38 to normal position and the peripheral portion of the mold face withdrawn into molding position.
- The back of the compression mold member desirably is provided with bosses 48 to receive studs carrying antifriction rollers 49 adapted to engage means for applying a gradually increasing pressure to the mold member. It will be noted that in the construction illustrated herein the receiving 85 mold faces are upon opposite sides of the central suction chamber 10 and the compression mold faces which coöperate with the receiving mold faces are consequently disposed opposite to each other. By reason of this construction compressive force applied to the oppositely disposed compression mold members may be utilized to force them equally toward the central mold receiving 90 faces so that power applied in compressing the pulp between the pairs of mold faces will be equally balanced and no lateral strain placed upon the arm which carries the receiving mold member, consequently there 95 will be no material vibration of the machine.
- In the construction disclosed in my prior patent the compressive force was applied to the backs of the oppositely disposed compression mold members by a pair of spring actuated rollers carried by a frame extending upwardly from the walls of the vat. These rollers engaged sharply inclined surfaces upon the backs of the compression mold members and in the operation of the machine imposed a strong compressive force 100 110 115 upon the mold members during a short interval in the rotation of the molds.
- The principal feature of the present invention consists in providing a means whereby a gradually increasing pressure is imposed upon the mold during a considerable period of its movement. A convenient mechanism which is illustrated herein comprises a frame consisting of oppositely disposed stands 51 of arcuate form, the lower 120 ends of the stands being rigidly anchored to the end walls of the vat or to the floor, as the case may be, and the upper end of said stands being connected by a cross beam 52. The stands 51 preferably are provided with 130

laterally extended webs 53 of gradually increasing width downward to strengthen the same against the lateral strains of the compression mechanism.

5 The means for applying compressive force to the compression members of the traveling mold desirably comprise two compressor plates which conform to the path of the traveling mold and are forced against the 10 same by gradually increasing pressure as the mold progresses along said plates. Where, as in the device illustrated in the drawing, the molds travel in a circular path, the compressor plates 54 are arcuate in form and 15 preferably extend through approximately a quadrant.

The compressor plates 54 desirably are yieldably mounted upon opposite sides of the path of the molds and preferably are 20 normally inclined to converge in the direction of movement of the molds. In order to provide a compressive force which is very light at the beginning of the compression and increases to a maximum at the end of 25 the compression the plates 54 are desirably backed by resilient means adapted to impose a progressively increasing pressure upon the molds as they advance. As illustrated herein, helical springs 55, 56, 57, 58, 30 59, 60, and 61 of successively greater strength are interposed between the compressor plates and the vertical faces of the stands 51, said springs being mounted upon bolts or studs 62 which are anchored in the 35 compression plates 54 and project through suitable apertures in the stand 51. Suitable means may be provided for adjusting the force of the springs so that each may be regulated to supply its proportionate share 40 of the compressive force.

By reason of this construction any desired gradually increasing compressive force may be applied to the molds as they progress along their path, furthermore the resistance 45 of the springs 55, 57, etc., permits sufficient yielding of the compressor plate to avoid breakage of the mold if any hard substance accidentally gets between the mold faces.

In order to remove the molded articles 50 from the machine, an endless apron 61 is located beneath the path of the compression mold member when it reaches discharging position. The molded article, when discharged from the compression member, 55 drops upon the conveyer and is removed in the manner described in my patent above referred to.

In the operation of the machine, the oppositely disposed receiving mold faces which 60 are carried by the radial arms 3 are dipped successively into the pulp in the vat. While immersed in the pulp, suction is applied through the hollow arm 3 and the layer of pulp sucked up upon the mold face. At 65 this time the cams 23 act upon the com-

pression mold arms to support them substantially at right angles to the arm 3 so that they do not enter the pulp in the vat. As soon as the mold emerges from the pulp in the vat, the cams 23 actuate the racks 21 70 and through them the gear segments 19 to cause the arms 17 to oscillate and to bring the compression members 16 into co-operative relation to the receiving mold members. As soon as the compression mold faces are 75 closed upon the layers of pulp adhering to the receiving faces, the mold enters between the lower ends of the compressor plates 54. The rollers 60 upon the compression members of the mold then engage 80 the compressor plates 54. During the further travel of the mold, the compressor plates exert a progressively increasing pressure upon the compression members of the mold thus slowly squeezing the water out of 85 the molded article. Upon further movement of the mold, the compressed air pipe 14 is supplied with compressed air and, almost immediately afterward, the suction is cut off from the suction chamber so that 90 any liquid or moisture remaining in the suction chamber or mold will be blown down the hollow arm 3.

The compressed air continues to act upon the mold after the same has passed beyond 95 the compression plates and the cams 23 have started to withdraw the compression mold member from the receiving mold member. This serves to remove the molded article from the receiving face and transfer it to the 100 compression face which retains it until the mold has reached discharging position which is illustrated in Fig. 2. At this time the compression member of the mold is inverted and is passing directly over the conveyer 61. 105

As the mold passes beneath the arm 41 it is engaged by the pin 40 which rides up upon the inclined surface 46 of said mold member until it reaches the aperture 39 when it drops into said aperture and impinging 110 upon the central portion 37 of the discharge plate or spider actuates the latter to advance the peripheral portion of the mold face and to deliver the molded article upon the conveyer.

It is to be understood that the construction disclosed herein is illustrative but not restrictive and that the same may be modified within the meaning and scope of the claims which follow.

Having thus described my invention, what I claim as new and desire to secure by Letters Patent is:

1. In a machine for molding pulp articles comprising a traveling mold having a plurality of separable members provided with co-operating mold faces, and means for introducing a layer of pulp between said mold faces; a stationary compressor secured against movement with the traveling mold 125 130

extending in substantial parallelism with the path of the mold through a considerable portion of said path and yieldable means for causing the same to apply a gradually increasing pressure to said mold members whereby the liquid content of the pulp will be gradually expelled.

2. In a machine for molding pulp articles comprising a traveling mold having a plurality of separable members provided with coöperating mold faces, and means for introducing a layer of pulp between said mold faces; a stationary compressor comprising plates extending in substantial parallelism with the path of the mold and a series of springs adapted to exert progressively increasing pressure upon said plates.

3. In a machine for molding pulp articles comprising a traveling mold having a plurality of separable members provided with coöperating mold faces, and means for introducing a layer of pulp between said mold faces; converging compressor plates backed by a series of resilient members of progressively increasing strength adapted to engage said mold members.

4. In a machine for molding pulp articles comprising a mold formed of a plurality of separable mold members having coöperating faces, means for causing said mold to travel in a circular path, and means for introducing a layer of pulp between said faces; a stationary frame having an arcuate compressor plate curved to conform to the path of the mold located adjacent said path and secured against movement with the traveling mold and yieldable means for causing said compressor plate to apply a gradually increasing pressure to the mold members whereby the fluid will be gradually forced from the pulp.

5. In a machine for molding pulp articles comprising a mold having a pulp receiving member and a compression member, means for causing said members to travel in a circular path, means for introducing a layer of pulp between said members, a stationary frame having an arcuate compressor plate in the form of a quadrant conforming to the path of the mold and located adjacent said path, and yieldable means for forcing said compressor plate into engagement with said compression mold member to cause a progressively increasing pressure to be applied to said mold during approximately a quarter of each cycle of its movement.

6. In a machine for molding pulp articles comprising a traveling mold formed of a plurality of separable mold members having coöperating receiving and compression faces, means for causing said mold to travel in a curved path and means for introducing a layer of pulp between the said mold faces, a stand curved to conform to the path of said mold located adjacent said path, a com-

pressor plate similarly curved carried by said stand and a series of resilient members of progressively increasing strength intermediate of said stand and said compressor plate.

7. In a machine for molding pulp articles comprising a traveling mold formed of a plurality of separable mold members having coöperating receiving and compression faces, means for causing said mold to travel in a curved path and means for introducing a layer of pulp between the said mold faces, a stand curved to conform to the path of said mold located adjacent said path, a compressor plate similarly curved carried by said stand and helical springs of progressively increasing strength interposed between said stand and said compressor plate.

8. In a machine for molding articles comprising a pivotal arm having a mold member presenting oppositely disposed pulp receiving faces and coöperating compression members having faces adapted to coöperate with the faces of said receiving member, means for actuating said arm to cause the mold members to travel in a circular path, means for supplying a layer of pulp to said mold receiving member, means for closing the compression members upon said layer of pulp and a frame having a pair of oppositely disposed arcuate compressor plates extending in substantial parallelism with the path of the mold and converging in the direction of movement of said mold, and means for exerting a yieldable progressively increasing pressure upon said mold members through substantially a quadrant of the movement of said mold.

9. In a machine for molding pulp articles comprising a traveling mold having a plurality of separable members provided with coöperating mold faces, and means for introducing a layer of pulp between said mold faces, a stationary compressor comprising plates extending in substantial parallelism with the path of the mold, springs adapted to exert progressively increasing pressure upon said plates and antifriction rollers carried by said mold members adapted to engage said plates.

10. In a machine for molding pulp articles, a mold comprising separable receiving and compression members having coöperating mold faces the face of said compression member comprising a rigid central section and a peripheral movable section telescopically mounted upon said central section and an actuating member for said movable section, resilient means between said central section and said actuating member adapted normally to retain said molded sections in molding position, the back of said compression mold member being apertured to permit an impinging instrumentality to strike said actuating member and thereby

cause the peripheral section to discharge the article from the mold.

11. In a machine for molding pulp articles comprising a traveling mold having a pulp receiving member and a compression member, said compression member being provided with a face having a rigid central section and a peripheral movable section telescopically mounted upon said central section, an actuating member for said movable section and resilient means between said actuating member and said central section adapted normally to retain said sections in molding position, and the back of said compression member being provided with a central aperture, means for introducing a layer of pulp between said mold members, means for forcing said mold members together to compress the mold between them and a spring actuated pin located in the path of the compression mold member adapted to ride up upon the back of said member, to enter the aperture in the back of said compression member and impinge upon said actuating member and thereby cause the peripheral movable section to discharge the molded article from said compression member.

12. In a machine for molding pulp articles comprising a traveling mold having

a pulp receiving member and a compression member, said compression member being provided with a face having a rigid central section and a peripheral movable section telescopically mounted upon said central section, an actuating member for said movable section and resilient means between said actuating member and said central section adapted normally to retain said sections in molding position, the back of said compression member being provided with a central aperture, means for introducing a layer of pulp between said mold members, compression plates extending in the direction of travel of said mold adapted to engage said mold members, means for imposing upon said plates a progressively increasing pressure whereby the plate will be gradually expelled from the pulp, a spring actuated pin located in the path of the compression mold member adapted to ride up upon the back of said member to enter the aperture in the back of said mold member and impinge upon the actuating means for the peripheral movable section to cause the same to discharge the molded article from said compression member.

In testimony whereof, I have signed my name to this specification.

FRANK W. WATERMAN.
